UNITED STATES PATENT OFFICE

SAMUEL SCHOFIELD, OF LIVERPOOL, ENGLAND

BOTTLE

Application filed February 23, 1929, Serial No. 342,180, and in Great Britain March 1, 1928.

The present invention relates to improvements in bottles and more particularly to those having a closure of the crown-cork type.

According to the present invention the usual flange over which the rim of the crown cork is engaged is recessed at one or more places around the flange so that a lessened resistance to the removal of the crown cork will be present at these places.

10 A flat-sided crown or ledge may be provided around the bottle below the rim of the crown cork to allow for the insertion of a coin for the removal of the cork, or again, one or more flat-sided depressions can be provided in the neck of the bottle at these places for the insertion of a coin.

Where such flat-sided depressions are provided we prefer to arrange the recessed portions in the flange at the top edge of the bottle at spaced distances away from the said straight-sided recess or recesses, that is to say, in the case of two recesses diametrically spaced on the bottle neck the recessed portions of the flange will be spaced at 90° away 25 from each other.

The invention is more particularly described with reference to the accompanying drawings in which:—

Figure 1 is a side elevation of one form of 30 bottle constructed according to the invention.

Figure 2 is a corresponding plan view.

Figure 3 is a fragmental sectional elevation on the line 3—3 of Figure 2.

Figure 4 is a sectional plan view on the line 35 4—4 of Figure 1.

As illustrated in the drawings, the flange 1 of the bottle is recessed as at 2 at three places spaced equidistantly on the circumference of the flange so as to lessen the resistance to removal of the crown cork from 40 the flange.

Depressions or notches 5, are provided equidistantly about the bottle neck immediately beneath the flange 1 for insertion of a 45 coin or the like for removal of the crown cork. The lower face or ledge 6 of each depression or notch is formed as a helical arc on the circumference of the bottle neck, that is to say, the said face or ledge is slightly 50 inclined relative to the flange 1.

Thus the distance between the crown cork and the ledge varies at different points on the ledge, so that a coin may be conveniently inserted between the cork and ledge at a point where this distance is relatively great, and then moved along the ledge into a position where this distance is smaller whereby removal of the cork is facilitated.

According to the present invention the upper or sealing face of the bottle neck is preferably of rounded or circular cross-sectional shape in order to assume efficient sealing of the bottle.

It is obvious that this invention may be applied to a jar or to a bottle having a neck of diameter substantially equal to the diameter of the base.

I declare that what I claim is:—

A receptacle having a neck adapted to be closed by a closure of the crown cork type comprising in combination a body, a flange 70 adapted to receive a crown cork, and recessed to lessen resistance to removal of a crown cork, and a number of recesses beneath said flange spaced intermediate and equi-distantly to the recesses in said flange.

In witness whereof, I have hereunto signed my name this sixth day of February 1929.

SAMUEL SCHOFIELD.
